UNITED STATES PATENT OFFICE.

FRANK H. KINNEY, OF HEMLOCK, NEW YORK.

FLAGSTAFF.

1,121,510.

Specification of Letters Patent. Patented Dec. 15, 1914.

Application filed March 26, 1914. Serial No. 827,354.

To all whom it may concern:

Be it known that I, FRANK H. KINNEY, a citizen of the United States, and a resident of Hemlock, in the county of Livingston and State of New York, have invented a new and Improved Flagstaff, of which the following is a full, clear, and exact description.

My invention relates to a novel flagstaff 10 constructed of telescoping sections to be distensible, or to be collapsed into small compass, the tubular base member constituting a container for the other collapsed sections. The uppermost section of the staff carries 15 a member which constitutes in the collapsed condition of the staff, a cap for the base section or container, and said member and the base section have co-acting means for receiving a fastening billet.

The invention has special reference to a flagstaff adapted for use on railroads, and provision is made on the base section, and in connection with the top member of the cap section, for tying the upper and lower 25 ends of a plurality of signal flags, as for instance, red, yellow and green flags. Between the top and bottom tying-means for the flags, sliding rings are provided for connection with the respective flags.

The invention will be more particularly explained in the specific description following.

Reference is to be had to the accompanying drawings forming a part of this specification, in which similar characters of reference indicate corresponding parts in all the views.

Figure 1 is a side elevation with parts in section, representing the staff in the distended position and indicating a portion of a flag thereon; Fig. 2 is a top plan view on an enlarged scale; Fig. 3 is a horizontal section taken adjacent to the lower end of the base section; and Fig. 4 is a side elevation of the staff in collapsed and fastened form.

In constructing a flagstaff a practical embodiment of my invention is illustrated. A tubular base section 10 is provided, closed 50 at its lower end by a base 11 in the form of a disk which extends laterally, presenting an annular projecting flange. The section 10 is slightly tapered, as are also a plurality of tubular sections 12, which are 55 of gradually reduced size from the top to the bottom of the staff. The several sec-

tions telescope one within another. The upper section 12 has a disk 13 thereon, which is adapted to constitute a cap for the base section 10, as shown in Fig. 4, when 60 the staff is collapsed and the sections 12 brought within the said base section.

A plurality of loops 14, preferably three in number, are formed on the base section 10 near the bottom. The said loops are integral with each other, being formed on a ring 15 within the said base section, the material of the ring being extended through the side of the base section at different points, to form said loops, as clearly shown 70 in Figs. 1 and 2. The loops provide for receiving a tie string 17 for the lower end of a flag 16, there being in practice, provision made for three flags. An upper tie string 17^a secures the upper end of each 75 flag to the disk 13, which latter is formed with three slots 18 therein for the purpose. Between the upper and lower ends of the flag, the latter is equipped with spaced rings 19 which may slide on the staff. 80

It will be noted that the disk 13 is below the upper end of the top section 12 of the staff, and the extreme upper end of said top section terminates in a button 20, leaving a short shank portion 21 between the disk and 85 the said button. The button 20 with its shank 21 is adapted to be engaged by the upper end of a fastening billet 22, and a co-acting button 23 is formed or secured on the exterior of the base section 10, for securing the lower end of the billet 22 when the staff is collapsed and the disk 13 is in position as a closure for the top of the base section, as shown in Fig. 4. 90

It will be seen that the construction provides for the ready securing of three flags, either one of which may be displayed, the other two being gathered in the hand of the user, or, as will be obvious, only one flag may be secured to one staff, and three 100 separate staffs employed for the separate flags.

Having thus described my invention, I claim as new, and desire to secure by Letters Patent:

1. A flagstaff comprising telescoping sections, the base section forming a container for the other sections, and the top section having a member forming a cap for the base section, and means for securing the cap 110 in place, said means consisting of a button on the top section above the cap member, a 105

button on the base, and a billet to engage said buttons.

2. A flagstaff comprising telescoping sections, the top section having a disk to constitute a closure of the base section, the disk having a plurality of slots in angular relation, and a ring in the base section formed with a plurality of integral loops at the outside of the base section, the slots and

loops constituting means to secure a plurality of flags at the top and bottom thereof.

In testimony whereof I have signed my name to this specification in the presence of two subscribing witnesses.

FRANK H. KINNEY.
